Patented Apr. 7, 1925.

UNITED STATES PATENT OFFICE.

CLAUDE H. SCHOOLEY, OF SIOUX CITY, IOWA.

FOUNTAIN PEN.

Application filed May 1, 1923. Serial No. 635,916.

To all whom it may concern:

Be it known that I, CLAUDE H. SCHOOLEY, a citizen of the United States, residing at Sioux City, in the county of Woodbury and State of Iowa, have invented a new and useful Fountain Pen, of which the following is a specification.

This invention is a self-filling fountain pen of the "pump" type.

- 10 One of the objects of the invention is to provide a fountain pen of the character mentioned, which will be of simple construction, made up of parts which will not readily wear out or be impaired in their operation
 15 by the corrosive action of the ink. A further object is to provide a fountain pen of maximum capacity, with a fluid-tight reservoir. A further object is to provide a pen so constructed that the filling operation will clean
 20 out the channels of the pen structure, and also mix the ink so that a solid color is maintained. A further object is to provide a fountain pen having means by which it may be carried upon the end of a chain
 25 or other flexible support, in a manner which will not impede its free manipulation in the hand while writing.

The invention will be hereinafter fully set forth and particularly pointed out in the claims.

In the accompanying drawing:—

Figure 1 is a longitudinal sectional view illustrating a fountain pen constructed in accordance with the invention. Figure 2 is an enlarged sectional view illustrating the plunger piston. Figure 3 is a detail view of one of the packing washers. Figure 4 is an enlarged view illustrating the cap.

Referring to the drawing, 10 designates the barrel of the pen, provided with the usual longitudinal bore internally threaded at the ends, as indicated at 11 and 12, respectively, the bore contiguous to the threaded end 12 being enlarged to provide a chamber 13. The threaded portion 12 is complementary to the threaded nipple 14, of the pen-carrying section 15, which is provided with a feed device 16, and the usual pen, which may be of any preferred or desired construction.

The threads of the end 11 are complementary to the threaded nipple 17 of a plunger knob 18, which is provided with a knurled portion 19. Secured within the knob 18 is a plunger rod, constructed of a metal core 20 surrounded by or encased within a non-

corrosive covering 21, such as hard rubber. Said plunger rod extends through the bores of a plurality of packing washers 22 and 23, the washers 22 being preferably constructed of hard non-corrosive material, such as hard rubber, and externally threaded to engage the threads 11 of the barrel. The washer 23 is of elastic material such as cork, and is preferably clamped between the washers 22. The washers are each provided in one face with recesses 24, to be engaged by a spanner wrench or the like. Said washers are so positioned that when the nipple 17 has been screwed home, it will bear against a washer 22.

The metal core 20 of the plunger rod is extended at one end beyond the covering 21, to provide a bearing portion 25, upon which a piston 26 is slidably mounted. The bearing 25 is somewhat longer than the piston 26, so as to permit of a slight longitudinal play, the end of the rod 20 being split as indicated at 27, to retain the piston in place. The bore of the piston through which the bearing portion 25 extends is of somewhat larger diameter than the diameter of the rod 20, so as to provide a passageway through the piston, said passageway being provided with a valve seat 28, which is closed by the valve-like end 29 of the covering 21, when the piston moves in one direction. By loosely mounting the piston upon the rod so that there can be relative longitudinal play, said piston will move in synchronism with the vibrations imparted to the barrel in writing and thereby cause ink to flow freely to the pen.

The pen end of the barrel is covered by a main cap 30, having an internally threaded portion 31, complementary to an externally threaded portion 32 of the barrel. The outer end of said cap is open, and contiguous to said end is provided with an internal annular shoulder 33, which is complementary to an external shoulder 34, of a swivel member 35, which extends through the open outer end of the cap 30. Said swivel member is provided with suitable means, such as sockets 36, to receive a clip 37, by means of which the cap may be connected with a chain or other flexible support.

When it is desired to fill the pen, the cap 30 is, of course, first removed. The knob 18 is then unscrewed and moved in a direction to withdraw the plunger rod. As the withdrawal of said rod progresses, the split

end 27 thereof engages the piston 26, and imparts corresponding movement thereto, until it abuts against the innermost washer 22. The plunger rod is then forced inwardly carrying with it the piston 26, the valve 29 engaging valve seat 28, a vacuum being created behind the piston during its return movement. At this time the pen end of the barrel is submerged in the ink 10 contained in a suitable reservoir. The instant that the air-tight joint is broken between the piston and the barrel, by movement of the piston into the enlargement 13 of the bore of the barrel, atmospheric pressure upon the ink immediately forces a sufficient quantity of said ink into the pen to fill the barrel. The knob 18 is then screwed into place and the pen is ready for use. It will be noted in this connection, that during 20 the movement of the piston 26 in the bore of the barrel after its withdrawal from the enlargement 13, the valve 29 uncovers the bore through said piston, allowing air to freely escape therethrough. Thus there is no air-cushion formed back of the piston to resist or impede its withdrawal to the extreme limit of its movement. During the 25 return movement of the piston, the valve 29 engages the seat 28, closing the air passage through the piston, making an air tight joint, and thereb insuring the formation of the necessary vacuum within the bore of the barrel.

The advantages of the invention will be 35 readily apparent. For instance, it will be observed that the pump device is of exceedingly simple construction, and the metal portion of the rod 20 is so protected that it will not be readily subjected to the corrosive 40 action of the ink. The non-corrosive covering 21, also serves to make an air-tight joint where the rod 20 passes through the washers 22 and 23, and yet permits said rod to reciprocate smoothly through said 45 washers with minimum wear. The washers 22 and 23, insure a fluid-tight packing through which the plunger rod may be operated without leakage, and their positions may be readily adjusted at any time 50 should they work loose. It will also be readily understood that the back and forth movement of the piston has the effect of cleaning out the channels at the open end of the device and to so agitate the ink that it 55 is thoroughly mixed, so as to insure solid color. By providing the piston with a bore which is open during its withdrawal movement and having no enlargements on the plunger rod to limit outward movement thereof, said piston may be moved to the 60 extreme end of the barrel, thereby exhausting practically all of the air in the bore when the piston is returned. In this manner a greater quantity of ink is stored within the 65 barrel than is possible with the usual type of

pump pen, because there has been a more complete exhaustion of the air than is possible where movement of the piston is interrupted before it reaches the end of the bore. By means of the swivel connection of the 70 cap, the latter may be placed over the knob end of the pen when it is desired to write with the same and the chain will not impede the use of the pen.

Having thus explained the nature of the 75 invention and described an operative manner of constructing and using the same, although without attempting to set forth all of the forms in which it may be made, or all of the forms of its use, what is claimed 80 is:—

1. A fountain pen comprising a barrel having a bore enlarged at one end, means for mounting the pen in the last mentioned end, a plunger rod mounted to reciprocate longitudinally within said barrel, and a piston loosely mounted on said rod and normally positioned in the enlarged portion of the bore when the pen is in use, whereby it may move in synchronism with vibrations 85 imparted to the barrel in writing and thereby cause the ink to flow to the pen.

2. A fountain pen comprising a barrel having a bore enlarged at one end, means for mounting the pen in the last mentioned 95 end, a plunger rod mounted to reciprocate longitudinally within said bore and having a portion at one end reduced in diameter, a piston having a bore receiving the reduced 100 end of said plunger rod and of larger diameter, said piston being shorter than said reduced portion and normally positioned in the enlarged portion of the bore when the pen is in use, whereby it may move in synchronism with vibrations imparted to the 105 barrel in writing and thereby cause the ink to flow to the pen.

3. A fountain pen comprising a barrel having a bore enlarged at one end, means for mounting the pen in the last mentioned 110 end, a plunger rod mounted to reciprocate longitudinally within said barrel, said plunger rod having a reduced portion at one end, and a piston shorter than the reduced portion of said plunger and having a bore receiving said reduced end but of larger diameter, said bore being provided with a valve seat to receive the contiguous increased-diameter portion of said plunger rod, said piston being normally positioned 115 in the enlarged portion of the bore when the pen is in use, whereby it may move in synchronism with the vibrations imparted to the barrel in writing and thereby cause ink to flow to the pen.

4. A fountain pen comprising a barrel having a bore enlarged at one end, means for mounting the pen in the last mentioned end, a plunger rod mounted to reciprocate longitudinally within said barrel and hav- 120

ing a split end, and a piston loosely mounted on said rod, whereby it may move in synchronism with vibrations imparted to the barrel in writing and thereby cause the ink 5 to flow to the pen.

5. A fountain pen comprising a barrel having a bore enlarged at one end, means for mounting the pen in the last mentioned end, a plunger rod mounted to reciprocate 10 longitudinally within said bore and having a portion at one end reduced in diameter, a piston having a bore receiving the reduced end of said plunger rod and of larger diam-

eter, said piston being shorter than said reduced portion and normally positioned in 15 the enlarged portion of the bore when the pen is in use, whereby it may move in synchronism with vibrations imparted to the barrel in writing and thereby cause the ink 20 to flow to the pen, and a noncorrosive covering for that portion of the plunger rod not engaged by the piston.

In testimony whereof I have hereunto set my hand.

CLAUDE H. SCHOOLEY.
